EXPANSION BIT

Alfred P. Albrecht, Wilmington, Ohio, assignor to
The Irwin Auger Bit Company, Wilmington,
Ohio, a corporation of Ohio

Application April 25, 1939, Serial No. 269,945

2 Claims. (Cl. 145—127)

This invention relates to an expansion bit which is provided with improved means for extending and retracting the extensible cutting element which determines the diameter of the hole to be bored.

It is the principal object of the present invention to provide in an expansion bit means for obtaining a micrometer adjustment of the expansion cutter with one hand.

10 It is another object to provide a device of the type just described wherein means is provided for locking the expansion cutter in any desired position of micrometer adjustment.

15 Still another object is to provide a device of the foregoing type wherein the micrometer adjusting means and the locking means are co-axial.

20 Another object is to simplify and render more economical the production of an expansion bit by rendering it necessary to cut only a dove tail slot in the body of the bit near the boring end thereof, while at the same time providing a stronger assembly.

25 Still another object is to provide means for extending and retracting the expansion cutter which comprises a rack on the slidably mounted expansion cutter and a rotatable pinion mounted on the body of the bit and cooperating with the rack in such manner that as it is rotated the expansion cutter is moved laterally with respect to the bit. Indicia may be provided for indicating the lateral position of the expansion cutter and means is provided co-axial with the pinion for locking the pinion and thereby the expansion cutter without disturbing in the slightest the adjustment of the pinion and expansion cutter.

30 Still other objects will appear as the description of the invention proceeds.

Referring to the drawing:

40 Figure 1 is a front elevation of an expansion bit constructed in accordance with the present invention.

Figure 2 is a rear elevation of the bit of Figure 1.

45 Figure 3 is a plan view of the bit of Figures 1 and 2.

Figure 4 is a section on the line 4—4 of Figure 1, looking in the direction of the arrows.

50 Figure 5 is a perspective view showing the extensible cutting element and the adjusting micrometer in cooperating relationship.

Referring to the drawing in detail, reference numeral 1 generally designates the body of the bit provided with spur 2 and fixed cutting edge 3 on its enlarged end 4 which is somewhat greater

5 than semi-cylindrical and which has a flat face 5.

Disposed transversely in the end 4 is a milled dove tail slot 6 which extends inwardly from face 5 and which is at a slightly oblique angle with respect to a plane normal to the axis of the bit. 5 This slot is formed by an unbroken face 7 which is adjacent the cutting edge 3 and by a face 8 opposite face 7. Face 8 is broken in its middle for a purpose which will presently appear.

Face 7 is provided with a stepped portion 9 10 which extends outwardly and towards cutting edge 3.

15 Slidably disposed in slot 6 is the expansion cutter generally designated 10 which is provided with cutting edge 11 which cuts that portion of 15 the bottom of the hole not cut by constant cutting edge 3, and with cutting edge 12 which determines the diameter of the hole being bored.

Expansion cutter 10 is provided with a slanting side 13 which is adapted to cooperate in sliding engagement with broken slanting face 8 of slot 6, with a slanting side 14 which is adapted to cooperate with slanting face 7 of dove tail slot 6, and with a flat inward face 15 which is adapted to slidably engage the bottom flat face 6a of slot 25 20 6. On the side next to cutting edge 3, the expansion cutter 10 is formed with a stepped portion 16 which is adapted to engage slidably with step or shoulder 9 formed adjacent face 7 of slot 6. This stepped portion 16 tends to keep dust 30 and chips from collecting between cutter 10 and slot 6. Cutting edges 11 and 12 are formed on this stepped portion 16.

As a result of the construction of slot 6 and cutter 10, these elements cooperate slidably and 35 form a very strong assembly, cutter 10 being firmly held from moving outwardly with respect to the body of the bit and operating therewith to prevent chips or dust from interfering with the 40 slidable action desired.

Disposed on the face of the cutter 10 which is away from spur 2 is formed a rack 17 extending parallel to the cutter. This rack comprises teeth 18 formed on slanting face 13 of cutter 10, the ends of the teeth being in the same plane with 45 face 13 and the recesses forming the teeth extending towards the face 14 of the cutter.

Rotatably mounted with respect to body 1 is a pinion generally designated as 19 which is provided with teeth 20 which cooperate with the 50 teeth 18 of rack 17. This pinion is in the form of a frustro-conical body, the teeth 20 extending the full length of the conical side which is equal to the depth of face 13. These teeth are formed over a semicircular arc of conical pinion 19 al- 55

though obviously an arc of any other desired length may be employed.

Pinion 19 is mounted rotatably in a generally frustro-conical recess 21 formed inwardly of flat 5 face 5 of body 4. This pinion 19 is so formed that its slanting wall 24 is adapted to tightly frictionally engage the slanting wall of recess 21 before its flat inward face 22 engages the flat inward bottom face 23 of recess 21. Thus it is insured 10 that pinion 19 will tightly frictionally engage body 4 by reason of the wedging action of the slanting face 24 of pinion 19 against the slanting wall of recess 21 as it is drawn inwardly, and will 15 thus be locked and lock cutter 10 firmly against motion relative to body 4.

Frustro-conical recess 21 is formed with an opening connecting it with slot 6. The bottom 20 23 of recess 21 is parallel to and lower than the bottom 6a of slot 6 in order to provide the clearance referred to above between face 22 of pinion 19 and face 23 of recess 21. Through the opening thus formed between slot 6 and recess 21, several teeth of pinion 19 project into engagement with cooperating teeth 18 of rack 17 on cutter 10.

25 Thus, as pinion 19 is rotated about its own central axis, cutter 10 is moved to and fro in slot 6, in this way providing adjustment of the size of the hole bored by the bit.

Pinion 19 is provided with an integral outwardly extending knurled knob or dial 25 which is knurled on its periphery 26. Thus, by turning knob 25 with the fingers, pinion 19 is rotated and cutter 10 is slid in slot 6.

30 In order to provide for firmly holding pinion 19 in immovable relationship with respect to the body 4 of the bit 1, a screw 26a extends from the rear of the body 4 through a hole 27 into screw-threaded engagement with a threaded hole in pinion 19 designated by 28. Thus, by loosening screw 26a slightly by means of a screw driver held in one hand, pinion 19 is freed of its frictional engagement with recess 21 and is free to be rotated with the other hand to the desired position when it may be secured in that position 45 by tightening screw 26a so as to draw pinion 19 inwardly into tight frictional engagement with recess 21.

By means of the rack and pinion, the operator 50 is able to quickly secure a very accurate positioning of cutter 10. By reason of screw 26a, the operator is able to lock the assembly in any desired position without disturbing this predetermined accurate positioning of cutter 10. This result is partially brought about by the fact that 55 screw 26a is co-axial with pinion 19. Screw 26a causes the pinion 19 to so tightly frictionally engage recess 21 as to overcome any tendency of the rotation of screw 26a to rotate pinion 19 during the tightening. The force with which 60 pinion 19 engages recess 21 is much greater than any force exerted by screw 26a tending to turn pinion 19 with it and to thereby disturb the adjustment of cutter 10. In other words, the frictional force with which conoidal wall 24 engages recess 21 is at any instant of greater magnitude than and is developed before the frictional force with which the threads of screw 26a engage the threads in threaded hole 28 of pinion 19.

65 In order to allow a very accurate determination of the diameter of hole to be bored by the bit, pinion 19 is provided with a locating index 29 and the surrounding peripheral portion of body 4 is provided with angularly disposed indicia 31 which are calibrated in terms of the degree of 70 extension of expansion cutter edge 12 or in terms

of the radius or diameter of the hole to be bored. If desired, the single index 29 may be placed on the body 4 and the angularly disposed indicia 31 placed on the periphery of pinion 19.

It is pointed out that as pinion 19 is drawn 5 inwardly by tightening screw 26a in pinion 19, pinion 19 exerts a force on cutter 10, pushing it towards the wall 7, step 9 and even against wall 30 above step 9, thereby holding the cutter 10 firmly against any tendency to twist in slot 10 6. However, when pinion 19 is freed by loosening screw 26a, cutter 10 is freed from this binding action just mentioned and is free to readily slide in slot 6.

15 It will be understood that it is necessary to turn screw 26a only a few turns in order to free or tighten pinion 19 and consequently cutter 10. Yet screw 26a can be easily tightened with very little effort to such an extent that cutter 10 is held absolutely against movement of any kind 20 relative to bit 1.

25 As will be seen from the drawings, the mechanism for adjusting and locking cutter 10, namely screw 26a and pinion 19, is all located within a very small compass, in fact within the compass 25 of the circle of the radius of body 4. Thus, the adjusting and locking mechanism clears the smallest hole which it may be desired to bore with the bit.

30 It will be understood that I desire to comprehend within my invention such modifications as may be necessary to adapt it to varying conditions and uses.

Having thus fully described my invention, what I claim as new and desire to secure by Letters 35 Patent is:

1. In an expansion bit, an expansion cutter which is laterally slidable with respect to the body of said bit and having a rack integrally formed thereon, a pinion the teeth of which engage said rack and which is rotatable with respect to the body of said bit, a gripping member integral with said pinion allowing said pinion to be readily rotated whereby to adjust the lateral position of said cutter, and a screw passing 40 through said bit body from the opposite side thereof and screw-threadedly engaging said pinion axially therewith and adapted to lock said pinion in any desired position of rotary adjustment, thereby locking said cutter in any desired 45 position of lateral adjustment.

2. In an expansion bit, an expansion cutter which is laterally slidable with respect to the body of said bit and having a rack integrally formed thereon, a pinion the teeth of which engage said 55 rack and which is rotatable with respect to the body of said bit, a knurled gripping member integral with said pinion allowing said pinion to be readily rotated whereby to adjust the lateral position of said cutter, and a screw passing 60 through said bit body from the opposite side thereof and screw-threadedly engaging said pinion axially therewith and adapted to lock said pinion in any desired position of rotary adjustment, thereby locking said cutter in any desired 65 position of lateral adjustment, said pinion having slanting conical walls and said bit body having slanting walls forming a conical recess co-operating with the slanting walls of said pinion to thereby cause said pinion to tightly frictionally engage said body portion by reason of the wedging action of said pinion in said recess when said screw is operated in a direction to lock said pinion.
